WATER TEMPERING SECTIONAL SPRAY HEAD

Filed May 23, 1927

UNITED STATES PATENT OFFICE

HERMAN E. HEINE, OF MILWAUKEE, WISCONSIN, ASSIGNOR TO BRADLEY WASH-
FOUNTAIN COMPANY, OF MILWAUKEE, WISCONSIN, A CORPORATION OF WISCONSIN

WATER-TEMPERING SECTIONAL SPRAY HEAD

Application filed May 23, 1927. Serial No. 193,536.

This invention relates to improvements in water-tempering sectional spray heads more particularly adapted for sanitary wash fountain use.

5 From an ordinary spray head only water of the same uniform temperature can be discharged. As a number of persons use wash fountains equipped with such a spray head, this is objectionable, due to the fact that the 10 temperature of the water satisfactory to one might not please the others.

It is one of the objects of the present invention to overcome the before-mentioned objectionable feature and provide a sectional 15 spray head having means for not only controlling the flow of water from different sections but also having means for mixing and controlling the temperature of the water flowing from each section of the spray head.

20 A further object of the invention is to provide a water tempering sectional spray head which is of simple construction, is strong and durable and is well adapted for the purpose described.

25 With the above and other objects in view the invention consists of the improved water-tempering sectional spray head, and its parts and combinations as set forth in the claims, and all equivalents thereof.

30 In the accompanying drawing in which the same reference characters indicate the same parts in all of the views:

Fig. 1 is a vertical sectional view of the 35 improved water tempering sectional spray head;

Fig. 2 is a horizontal sectional view taken on line 2—2 of Fig. 1, the valves being removed; and

Fig. 3 is a similar sectional view taken on line 3—3 of Fig. 1.

Referring to the drawing the numeral 5 indicates the spray head casing which is formed with a body portion 6, a bottom portion 7 and a top portion 8 secured together by bolts 8'. Gaskets 9 and 10 are interposed between the body portion and the bottom and top portions to form water tight joints therebetween.

50 The lower side of the bottom portion is formed with an outer recess or chamber 11

and an inner recess or chamber 12 separated from the outer chamber by an irregular shaped partition 13 having four extensions 14 which terminate a short distance from the outer wall or flange 15 of the body portion 55 forming the outer chamber 11. Water inlet pipes 16 and 17 extend downwardly through openings 16' and 17' in the top portion 8 and into the body member and having a threaded connection therewith, the pipe 16 communicating with the chamber 12 and the pipe 17 communicating with the chamber 11. The bottom portion 7 forms the lower wall of said chambers 11 and 12 and the gasket 9 provides a seal between the partition 13 and the flange 15 and the said bottom portion 7. While either pipe 16 and 17 may be used for the hot water supply, the pipe 16 connected to the inner chamber 12 is preferably used for hot water and the pipe 17 connected to the chamber 70 is used for the cold water supply. A projection or boss 18 extending downwardly from the bottom portion 7 and having a threaded bore 19 is provided for connection with a means of support (not shown) and the 75 top portion 8 is also provided with an externally threaded projection or bore 20 for connection with an upper support (not shown). The upper portion of the body member 6 is formed with radial partition 80 walls 21 and an outer peripheral flange 22 to form segmental spaces 23 therebetween, and said spaces are divided by irregular shaped partitions 24 to form in connection with the top portion 8 mixing spaces or chambers 25 85 and discharge spaces or chambers 26 which are connected to the chambers 25 by openings 27 extending through the partitions. The outer peripheral flange 22 is provided with outwardly and downwardly extending jet 90 openings 28 for discharging jets of water therethrough from the discharge chambers 26.

Valves 29 extending through the top portion 8 and threaded openings 30 in the body portion 6 are in communication with the cold water chamber 11. The valves 29 also have ports 31 opening communication with the mixing chambers 25 so that when the handles 32 are turned to open the valves the cold 100

water can flow from the cold water chamber 11 to the mixing chambers 25. Other valves 33 extend through the top portion 8 and threaded openings 34 of the body portion 5 connect with the hot water chamber 12. The said hot water valves 33 also have ports similar to the ports 31 which also open into the mixing chambers 25 so that when the handles 35 of said valves are turned into open position 10 the hot water from the hot water chamber 12 can also enter the mixing chambers 25 and temper the cold water therein, and as there is a mixing chamber for each quarter section of the spray head the temperature 15 of the water flowing from each section can be controlled by the valves for each section. Furthermore, each individual user can control the flow of water from a particular section so that water will not be wasted in flowing 20 from sections not in use.

While only one form of the spray head is shown and described, it is to be understood that the form may be changed or modified without departing from the spirit and scope 25 of the invention.

From the foregoing description it will be seen that the water tempering sectional spray head is of very simple construction and is well adapted for the purpose described.

30 What I claim as my invention is:

1. A spray head, comprising a casing divided by partitions to form a plurality of upper sections and lower compartments and having spray discharge openings for each 35 section, independent valves for each section for individually controlling the flow of water from the lower compartments to the upper sections and thereby controlling the temperature and flow of water discharged through 40 the spray openings of each section, means for supplying cold water to one of the lower compartments, and means for supplying hot water to the other lower compartment.

2. A spray head, comprising a casing divided by partitions to form a plurality of upper sections and lower compartments and having spray discharge openings for each section, some of the upper sections forming individual mixing chambers for some of the 50 hot and cold water, independent valves for controlling the flow of hot and cold water from the lower compartments to the mixing chamber of each section and thereby controlling the temperature and flow of water discharged through the spray openings of each section, means for supplying cold water to one of the lower compartments, and means for supplying hot water to the other lower compartment.

60 3. A spray head, comprising a casing formed of a body portion and top and bottom portions connected thereto, said casing having partitions forming lower hot and cold water compartments and also having upper 65 partitions forming sections, each of which

include a mixing chamber, and a discharge chamber in communication therewith, the casing also having spray openings in communication with the discharge chambers, independent valves for controlling the flow 70 of hot and cold water from the lower compartments to the mixing chamber of each section and thereby controlling the temperature and flow of water discharged through the spray openings of each section, means 75 for supplying cold water to the lower cold water compartment, and means for supplying hot water to the lower hot water compartment.

4. A spray head, comprising a casing 80 formed of a body portion and top and bottom portions connected thereto, the upper part of said body portion providing sections and each section having an inner mixing chamber and an outer discharging chamber, 85 said casing having spray openings in communication with the discharge chambers, the lower part of said body portion providing a cold water chamber and a hot water chamber, a cold water supply pipe for the lower 90 cold water chamber, a hot water supply pipe for the lower hot water chamber, and independent valves for controlling the flow of hot and cold water from the lower compartments to the mixing chamber of each section 95 and thereby independently controlling the temperature and flow of water discharged through the spray openings of each section.

5. A spray head, comprising a casing 100 formed of a body portion and top and bottom portions connected thereto, the upper part of said body portion being recessed to form sections having inner mixing chambers and outer discharge chambers in communication therewith, the peripheral part of the 105 body portion having spray openings in communication with the discharge chambers, the lower part of said body portion being recessed to form a cold water chamber and a hot water chamber, a cold water supply pipe 110 for the lower cold water chamber, a hot water supply pipe for the lower hot water chamber, and independent manually operated valves connecting each mixing chamber to the hot and the cold water chambers and thereby 115 independently controlling the temperature and flow of water discharged through the spray openings of each section.

6. A spray head, comprising a casing 120 formed of a body portion and top and bottom portions connected thereto, the upper part of said body portion being recessed to form sections having inner mixing chambers and outer discharge chambers in communication therewith, the peripheral part of the body 125 portion having a line of segmental spray openings in communication with the discharge chambers, the lower part of said body portion being recessed to form a cold water chamber and a hot water chamber, pipes ex- 130

tending through the top portion and threaded into the body portion for supplying hot and cold water to the lower chambers, and independent manually operated valves connecting each mixing chamber to the hot and cold water chambers and thereby independently controlling the temperature and flow of water discharged through the segmental spray openings of each section.

- 10 7. A spray head, comprising a casing divided by partitions to form a plurality of compartments and sections and having spray discharge openings in communication with said sections, independent valves for each 15 section for individually controlling the flow of hot and cold water from the compartments to the sections and thereby the flow and temperature of the water discharged from each section, means for supplying hot water 20 to one of the compartments, and means for supplying cold water to the other compartment.

In testimony whereof, I affix my signature.
HERMAN E. HEINE.
